UNITED STATES PATENT OFFICE.

GROVER C. FRANTZ, OF HARRISBURG, PENNSYLVANIA.

DISH-WASHING DEVICE.

1,358,192.

Specification of Letters Patent.

Patented Nov. 9, 1920.

Application filed May 31, 1919. Serial No. 301,048.

To all whom it may concern:

Be it known that I, GROVER C. FRANTZ, a citizen of the United States, residing at Harrisburg, in the county of Dauphin and State 5 of Pennsylvania, have invented certain new and useful Improvements in Dish-Washing Devices, of which the following is a specification.

One object of my invention is to provide 10 an easily operative dish washing device which can be placed in a tub or a sink, such for example as the tub shown in my co-pending application for patent Serial No. 301,047, filed May 31, 1919.

Another object is to make my invention 15 of a strong and durable construction and so that it can be used for thoroughly washing a large number of dishes at the same time and as such is particularly useful for 20 household purposes.

A still further object is to provide my improved dish washing device with handles which can be easily manipulated to oscillate the basket or body portion of the device 25 in a tub of soapy water and afterward used to lift the entire device into another tub or compartment having clear rinsing water therein so that by again oscillating the basket, the dishes can be thoroughly 30 rinsed.

Another object is to make my device of such construction that during the oscillation thereof water can freely pass through the body portion so as to engage all of the 35 dishes, both at the sides and bottom of the body portion.

A still further object is to make my improved device of such construction that it can be easily manufactured and put together 40 and so that the basket portion can be readily detached from the base section for cleaning purposes.

These objects, and other advantageous ends which will be described hereinafter, I attain 45 in the following manner, reference being had to the accompanying drawings in which—

Figure 1 is a front elevation of my improved dish washing device,

Fig. 2 is a top plan view of Fig. 1,

Fig. 3 is an inverted plan view of Fig. 1,

Fig. 4 is an enlarged fragmentary elevation of certain of the parts of my invention,

Fig. 5 is a section taken on the line 5—5 of Fig. 4 and showing a part of the handle 55 in outside view,

Fig. 6 is a section taken on the line 6—6 of Fig. 4,

Fig. 7 is a section taken on the line 7—7 of Fig. 4,

Fig. 8 is a fragmentary sectional elevation of the base and bottom portion of the basket and taken centrally through the device,

Fig. 9 is an enlarged fragmentary section taken on the line 9—9 of Fig. 8,

Fig. 10 is a fragmentary plan view showing means for rotatably locking the basket to the base; said means being operative to permit the ready detachment of said basket from the base, and

Fig. 11 is a section taken on the line 11—11 of Fig. 10.

Referring to the drawings, 12 represents a base which is preferably made of sheet metal which is stamped so as to provide 75 openings 13 and diagonally extending strips 14, said base being flanged as shown at 15 to serve as a reinforcement or strengthening means so that comparatively thin sheet metal can be used and at the same time provide a 80 strong base capable of withstanding a great weight. The base includes a central disk portion 16 which is slightly elevated above the outer frame portion 17 of the base so that the openings 13, when the device is set 85 in a tub of water, permits a circulation of water under the base and also upwardly through a perforated bottom 18 of a basket 19; the upper portion of said basket being 90 preferably made of woven wire fabric or screening so as to provide perforations or openings 20 to permit water to pass into the basket from the sides thereof.

A pivot pin 21 extends through the bottom 18 and through the disk 16 so that the basket 95 is pivotally supported on the base 12. A spacing washer 22 is interposed between the bottom 18 and the disk 16 for the purpose of reducing friction and also for the purpose of permitting water to pass through the 100 perforations in the bottom 18. The pivot pin 21 at a position below the disk 16 has an annular groove 23 into which is adapted to be swung a latch 24; said latch being pivoted at 25 to the bottom of the disk 16. The 105 latch 24, as clearly shown in Figs. 10 and 11, is so constructed that, when swung in the position shown in full lines in Fig. 10, a portion of the latch will enter the annular groove 23 and jam against a portion of said 110

pivot pin of reduced diameter as indicated by the dotted circle 26 in Fig. 10. Thus the pivot pin is securely held to the base and the basket 19 freely rotates on the upper portion of said pivot pin.

The basket 19 has an upper rim 27 which consists of a ring of malleable metal which is made of a strip which is folded upon itself so as to provide two folds 28 and 29. 10 The strip thus folded is bent so that the folding edge portion 30 extends outwardly and provides a flange.

Two posts 31 are positioned diametrically opposite each other and have portions 32 of reduced diameter which pass through the flange 30. These portions 32 are screw threaded, and nuts 33 are screwed thereon and bind the posts to the flange 30. The upper ends of the posts 31 have 15 handles 34 which are pivoted between their ends on the posts 31, and said handles are 20 freely rotatable on said posts and shaped to permit a secure hand-hold by a person who intends to operate the device. By having the handles 34 thus mounted, a person 25 by substantially straight and parallel movements of the arms can oscillate the basket 19 without any twisting action of the hands. This renders the oscillation of the basket 30 particularly easy and convenient.

The upright or vertical wires 35 have their upper ends positioned between the folds 28 and 29 and as clearly shown in Figs. 4 to 7 inclusive a secure and strong 35 mounting is thus provided; the outer fold preferably being bent or looped outward at 36 to permit entrance of the upper ends of the wires 35 between the folds 28 and 29 of the rim 27. These wires can be brazed, 40 soldered, welded or otherwise suitably connected to said rim.

The bottom 18 of the basket has a plurality of tongues 37 formed thereon which are spaced apart and bent around a wire core 45 ring 40. The vertical wires 35 of the basket have their ends 41 turned, in the form of eyelets, around the core ring 40 and these eyelets are positioned within the spaces between the tongues 37. Thus the bottom 18 50 is securely held to the upper or body portion of the basket and at the same time there are no projections which will interfere with the proper cleaning of the basket which will mar or injure the dishes.

55 In the operation of my invention, the device as previously stated can be set in a tub

of soapy water and the dishes can be piled in the basket 19. The basket can then be oscillated through the medium of the handles 34 and in so doing the water will 60 be forced through the perforations in the basket and thoroughly wash the dishes. The basket with the base attached can then be bodily lifted into another tub of rinsing water and by imparting a few oscillations to 65 the basket in the rinsing water, the dishes can be thoroughly rinsed.

If it is desired to detach the basket from the base, the same can be done by swinging the latch 24 so as to disengage the groove 70 23 after which the basket can be easily lifted from said base.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly 75 come within the scope of the appended claims.

Having thus described my invention, what I claim as new and desire to secure by Letters Patent is:—

85 1. A dish washing device including a base; a perforated basket pivotally supported on the base; and transversely extending handles pivotally connected to said basket so as to swing in a substantially horizontal plane whereby the handles can be grasped by the hands to impart an oscillating movement to the basket without materially changing the transverse positions of said handles; substantially as described. 95

2. A dish washing device including a base; a perforated basket pivotally supported on said base; upright posts connected to said basket; and transversely extending handles pivotally connected between 100 their ends to said posts at a position above the top of said basket and so as to swing in substantially horizontal planes; substantially as described.

105 In testimony whereof I have signed my name to this specification in the presence of two subscribing witnesses.

GROVER C. FRANTZ
